MACHINE FOR COATING STRIPS

Walter P. Osgood, Malden, Mass., assignor to
 Boston Machine Works Company, Lynn, Mass.,
 a corporation of Massachusetts

Application September 13, 1941, Serial No. 410,668

5 Claims. (Cl. 91—51)

This invention relates to a machine for applying cement to both sides of a strip of indeterminate strength, and more particularly to a modified form of the machine described and claimed in my copending application Serial No. 407,593, filed August 20, 1941. While this invention may apply to the coating of strips in general, it relates especially to strips of braided or plaited jute strands such as are used in making rope soles for shoes. Such strips have in the past been made into soles by being folded and wound upon themselves and then stitched so that the edges of the strip form the broad faces of the sole. Instead of stitching the folds or convolutions together, a suitable cement may be used.

In forming a rope sole for a shoe of a given size and width, a definite length of strip is required. The proper length is cut off from a strip of indeterminate length and is folded or wound upon itself in successive convolutions in such a manner as to form the proper shape for a shoe sole. In order to hold the convolutions together, the faces of the strip are coated with a suitable cement, such as a latex preparation, the strip being folded and wound into the form of a sole while this cement is still in its adhesive state. It is desirable that the final or outer convolution of the sole have its outer face free from cement since such outer face constitutes the boundary edge of the sole itself.

It is an object of the present invention to provide apparatus for applying coating to both faces of a strip, the coating on one of these faces being interrupted at predetermined intervals so as to leave an uncoated area on one face which will be the uncoated outer edge of a shoe sole after the strip has been wound into the shape of a sole.

As it is also desirable that the faces of the rope sole be free from cement, the apparatus hereinafter described is preferably formed to apply to each face of the strip a band of coating material or cement which is narrower than the width of the strip itself, so that the cement does not extend to either edge of the strip.

It is a further object of the invention to provide apparatus for the purpose described which is arranged in such a way as to economize on floor space and which is easily set up, operated and adjusted.

For a more complete understanding of the invention, reference will be had to the following description of the embodiments thereof and to the drawings, of which—

Figure 1 is an end elevation, partly in section, of a machine embodying the invention.

Figure 2 is a plan view of the same.

Figure 3 is a side elevation of the same.

Figure 4 is a section on the line 4—4 of Figure 2.

Figure 5 is an elevation of a portion of the mechanism shown in Figure 2.

Figure 6 is an elevation of a portion of the machine showing the interrupter mechanism.

Figure 7 is a section on the line 7—7 of Figure 6.

Figure 8 is an elevation of a portion of the machine shown in Figure 3, the movable guide wheel being shown in its elevated position.

Figure 9 is an end elevation of the portion of the mechanism shown in Figure 8.

Figure 10 is a section on the line 10—10 of Figure 2.

Figure 11 is a section on the line 11—11 of Figure 10.

The apparatus may be mounted on a suitable base 10 and, as shown, includes a casting 12 which may be used as a reservoir for certain kinds of liquid coating materials. In the present instance, however, a pool of latex cement is preferably maintained in a receptacle 14 by connection through a pipe 16 to a suitable constant-level source (not shown) such as an inverted bottle supported with its mouth in a pool communicating with the pipe 16. Partially submerged in the pool of cement in the receptacle 14 is a coating roll 18 which, as indicated in Figure 5, may be provided with a pair of cylindrical coating elements 20 and 22, which are axially spaced. These elements are of greater diameter than the remainder of the roll and are preferably narrower than the width of the strip 24 which is to be coated.

Directly over the coating element 40 is mounted a wheel or disk 30 having a periphery of approximately the same width as that of the strip 24. This wheel is spaced above the coating element 20 by a distance slightly less than the thickness of the strip 24 so that, when the strip is fed between the wheel 30 and the element 20, it is pressed against the latter so as to ensure positive kissing engagement therewith, whereby a film of cement is transferred from the element 20 to the under face of the strip 24. A doctor 28 is mounted adjacent to the peripheries of the elements 20 and 22 to regulate the thickness of the films of cement carried thereby.

The guide wheel 30 is provided with a number of sharp pins or points 31 projecting radially

from its periphery or is otherwise formed or equipped to prevent slipping of the strip 24 on the periphery of the wheel. As hereinafter described, a suitable feeding means is provided for advancing the strip 24 so that the wheel 30 is driven by the strip 24 and is kept positively in step therewith by the points 31. The guide wheel 30, in turn, drives a mechanism by which it is periodically elevated to interrupt the application of coating to the strip. As indicated in Figures 1 and 6, the guide wheel 30 and a coaxial pulley wheel 32 are secured to a spacer member 33 to rotate as a unit on a fixed shaft 34. This shaft is mounted in the free end of an arm 35 which is pivoted at 36 to a vertically adjustable cross-bar 37 secured to a pair of standards 38 on the base 10. The shaft 34 has an extension 40 which normally rests on the bar 31 and thus limits the downward rocking movement of the arm 35 which carries the shaft 34 and wheels 30 and 32. The height of the bar 37 is adjusted to space the guide wheel 30 the correct distance above the coating element 20 when the extension 40 of the shaft is resting on the bar as indicated in Figure 1. The wheel assembly 30 and 32 is also supported by an idler wheel or disk 41 which is directly beneath the pulley wheel 32 and in a common plane therewith. A belt 42 extends partly around the pulley wheel 32 and passes between the peripheries of the wheels 32 and 41 so that the portion of the belt 42 which is tangent to the wheel 41 helps to support the wheel 32. A predetermined portion of the belt 42 is thickened as at 43, and when this thickened portion enters between the wheels 32 and 41, it elevates the wheel assembly, as indicated in Figures 8 and 9, so as to increase the space between the peripheries of the wheel 30 and the coating element 20. A leaf spring 44 (Figure 8), which presses against the lower face of the strip 24 near the bite between the wheel 30 and the coating element 20, lifts the strip 24 clear of the coating element 20, so that as long as the guide wheel 30 is in its elevated position, no coating is applied to the strip by the element 20. The length of the belt 42 is such that while the element 43 is traveling from an initial position around the pulley wheel 32 and back to the same position, a length of the strip 24 just sufficient for one shoe sole will pass through the bite between the wheel 30 and coating element 20. The length of the thickening element 43 of the belt 42 is such as to leave an uncoated area on the strip 24 of the same length as the outermost convolution of the strip when made up into a shoe sole. Thus belts of different lengths are used for preparing the strip for soles of different sizes, and thickening elements 43 are correspondingly varied in length according to the outermost convolutions in soles of different sizes.

To support the belt 42 properly, an idler pulley 45 may be mounted in line with the pulley 32 on a standard 46 which is adjustable on ways 47 (Figures 6 and 7) toward or from the pulley 32 so that there will be sufficient tension on the belt 42 to avoid slipping on the pulley 32. In this manner the travel of the element 43 is kept in step with that of the strip 24 so that the periodic gaps in the coating applied to the latter occur at correct intervals.

The wheel 41 is supported by any convenient means such as a cross-bar 48 which is carried by a pair of brackets 49 adjustably secured to the standards 38.

After one face of the strip 24 has been coated,

as hereinbefore described, it is desirable to apply coating to the opposite face. To this end, the strip is led around the periphery of the wheel 30, the uncoated face of the strip being in contact with the periphery of the wheel. As shown in Figure 3, the strip 24 passes from the periphery of the wheel 30 to an idle guide pulley 50. The lowermost point of the guide pulley is substantially on a level with the lowermost point of the wheel 30. As shown in Figure 2, the guide pulley 50 is offset from the plane of the wheel 30 sufficiently to guide the strip 24 in a path parallel to the portion of the strip approaching the bite between the element 20 and the wheel 30. In passing from the idle guide pulley 50 to the coating element 22 of the roll 18, the strip 24 is inverted by being twisted through a half turn, so that when it reaches the element 22, its uncoated side will be presented to this element to receive the coating therefrom. The pulley 50 is mounted on an inclined axis, as shown, to guide the strip to its inverting movement. Directly above the coating element 22 is a suitable feed wheel 52 which is preferably provided with a knurled periphery having a series of points 54 adapted to sink into the upper face of the strip so as to ensure a positive feeding of the strip with minimum disturbance of the coating on this face. The feed wheel 52 is mounted on a driven shaft 56 which is supported by an arm 60, which is rockable to raise the feed wheel clear of the strip 24 for removal or replacement of the strip in the apparatus.

As shown in Figure 1, a gear wheel 62 is mounted on the shaft 56, this gear wheel meshing with a gear wheel 64 mounted on a shaft 66 which also carries a pulley wheel 68. The shaft 66 extends across the casting 12 and drives the coating roll 18. The pulley 68 is connected by a suitable train of belts and pulleys, indicated generally as 70, to a pulley 72 mounted on the shaft of a suitable motor 74 supported on a frame 76, or to any other suitable source of power. The pulleys in the train 70 can be readily replaced, if desired, by pulleys of different sizes to alter the speed ratios between the motor and the shafts which drive the feed wheel 52 and the coating roll 18.

The arm 60 is rockable about a pivot 80 to permit the operator to lift the feed wheel 52 clear of the strip 24. The arm 60 is normally pressed toward its operative position by its own weight and also by a coiled spring 82. The space between the feed wheel and the coating element 22 is determined by an adjustable stop element 84 carried by the arm 60.

The casting 12 may be provided with a removable cover 86 which is rockable about the pivot 88 and is normally held in its closed position by a pair of screws and thumb nuts 88. When the cover is swung upward, an abutment element 89 thereon supports the shaft 56 and its arm 60. Suitable guides 90 are provided to ensure proper registration of the strip 24 with the periphery of the wheel 30. Guides 92 are also provided to maintain the strip properly aligned between the feed wheel 52 and the coating element 22. A suitable guide 94 may also be provided to guide the strip 24 as it comes from a bale toward the nip between the wheel 30 and the coating element 20.

In setting up the apparatus for operation, a belt 42 of suitable length and having a thickening element 43 of the proper length for the size of the shoe sole to be made is mounted on the

pulley wheels 32 and 45, the supporting bracket 46 being adjusted to tension the belt 42 properly. The end portion of a braided jute strip may be pulled out from a bale of such strip and threaded between the guides 90 and between the guide wheel 30 and the coating element 20, the wheel 30 being manually raised to facilitate this threading operation. The strip is then led around the wheel 30 and around the idler pulley 50 in the manner indicated in Figure 3. The strip is then twisted a half turn and is led between the guides 92 and the under feed wheel 52. The latter can be raised by rocking the support arm 60 upward. Cement is supplied to the receptacle 14 through the pipe 16. The apparatus is then ready to be put into operation.

It is evident that various modifications and changes may be made in the embodiment of the invention herein shown and described without departing from the spirit or scope thereof as defined in the following claims.

What I claim is:

1. A machine for coating a strip, comprising a rotatable coating roll, a rotatable guide wheel on an axis parallel to that of said roll and normally in a position to press against the roll a strip passing between said wheel and roll, means normally pressing said wheel toward said roll, means periodically moving said wheel away from said roll during the operation of the machine, and means for inverting the strip after it has passed between said wheel and roll and leading it back to said roll to present its other side thereto.

2. A machine for coating a strip, comprising a rotatable coating roll, a rotatable guide wheel on an axis parallel to that of said roll and normally in a position to press against the roll a strip passing between said wheel and roll, means normally pressing said wheel toward said roll, means driven by rotation of said wheel periodically moving said wheel away from said roll during the operation of the machine, and means for inverting the strip after it has passed between said wheel and roll and leading it back to said roll to present its other side thereto.

3. A machine for coating a strip, comprising a

rotatable coating roll, a rotatable guide wheel on an axis parallel to that of said roll and normally in a position to press against the roll a strip passing between said wheel and roll, means normally pressing said wheel toward said roll, means periodically moving said wheel away from said roll during the operation of the machine, means for inverting the strip after it has passed between said wheel and roll and leading it back to said roll to present its other side thereto, and strip-feeding means engaging the strip where it makes its second contact with said roll.

4. A machine for coating a strip, comprising a rotatable coating roll, a rotatable guide wheel on an axis parallel to that of said roll and normally in a position to press against the roll a strip passing between said wheel and roll, means normally pressing said wheel toward said roll, means driven by rotation of said wheel periodically moving said wheel away from said roll during the operation of the machine, means for inverting the strip after it has passed between said wheel and roll and leading it back to said roll to present its other side thereto, and strip-feeding means engaging the strip where it makes its second contact with said roll.

5. A machine for coating a strip, comprising a coating roll rotatable on a horizontal axis, a rotatable guide wheel mounted above said roll and adapted to press against the roll a strip passing between the wheel and roll, means on the periphery of said wheel to ensure positive driving of the wheel by a strip moving between it and the coating roll, and means for periodically lifting said wheel away from said roll, said lifting means comprising a pulley mounted coaxially with said wheel to rotate therewith as a unit, an idle wheel below and in the same plane with said pulley, a belt of predetermined length passing around said pulley and engaging on the top of said idle wheel to support said pulley and guide wheel, said belt having a thickened portion of predetermined length to lift said pulley when it passes between said pulley and said idle wheel, and feeding means engaging the strip after it passes the guide wheel.

WALTER P. OSGOOD.
